UNITED STATES PATENT OFFICE.

GEORGE A. FAIR, OF LOS ANGELES, CALIFORNIA.

LOCK-ACTUATING MECHANISM.

1,162,229.

Specification of Letters Patent. Patented Nov. 30, 1915.

Application filed April 30, 1914. Serial No. 835,524.

To all whom it may concern:

Be it known that I, GEORGE A. FAIR, citizen of the United States, residing at Los Angeles, in the county of Los Angeles and State of California, have invented certain new and useful Improvements in Lock-Actuating Mechanism, of which the following is a specification.

My invention relates to locking mechanism and particularly to mechanism for throwing a plurality of bolts in different directions, this mechanism being particularly adapted for use with the form of combined door and window shown in my pending application Serial No. 807,527, filed on the 18th day of Dec., 1913. In this application for patent there is illustrated an improved form of window which also may be used as a door and in which the window (or door) is provided with pintles on opposite sides which are adapted to be projected into the window casing so that the window may be opened either from the right side or left side, as may be desired. In this prior application these pintles were shown as being detachable and shiftable from one side of the window casing to the other. In this application there is also shown a locking device whereby the window might be locked in the casing.

One object of my invention is the provision of locking means adapted particularly for use in connection with the above described window, so constructed as to control the operation of pivot bolts or pintles on opposite sides of a window or door and so control the operation of bolts whereby the door or window may be locked to the window casing, it being understood, however, that the pivot bolts or pintles themselves act as locking bolts under certain circumstances.

A further object of the invention is to so construct the locking mechanism above referred to, that it may be applied to a large variety of structures and used for throwing or retracting a plurality of bolts.

Still another object of the invention is to so construct the locking mechanism, above referred to, that two actuating devices or keys must be used to completely retract all of the bolts, one of these locking devices

actuating the longitudinally movable bolts which form the pintles or pivot bolts when the device is used for a window or door and the other controlling the latching bolt.

A further object of the invention is to simplify locking mechanism of the character described, reduce its cost, render it easy of operation and reduce liability of the parts getting out of order.

Other objects will appear in the course of the following description.

My invention is illustrated in the accompanying drawings, wherein:

Figure 1 is a front elevation of a pivoted window of the casement type, the sash-frame being shown partly in section so as to show the bolt mechanism within the sash-frame. Fig. 2 is an enlarged transverse section on the line 2-2 of Fig. 1. Fig. 3 is a vertical section on the line 3-3 of Fig. 2. Fig. 4 is a vertical section on the line 4-4 of Fig. 2. Fig. 5 is a perspective detail view of the locking mechanism, the parts being separated from each other. Fig. 6 is a top plan view of the door, the casing of the door being shown in section showing the application of my locking mechanism thereto. Fig. 7 is a front elevation of a door, constructed as in Fig. 6, the casing being shown in section. Fig. 8 is a section on the same lines as Fig. 4, but showing a modification of the lock construction particularly adapted to doors. Fig. 9 is a horizontal section of a safe deposit box showing my bolt mechanism applied thereto, and Fig. 10 is a vertical section on the line 10-10 of Fig. 9. Fig. 11 is a cross section on the line 11-11 of Fig. 8.

Corresponding and like parts are referred to in the following description and indicated in all the views of the accompanying drawings by the same reference characters.

Before describing the detailed construction of the locking mechanism, I will first describe one of the structures to which the locking mechanism is peculiarly adapted, this being the window structure illustrated and described in detail in my pending application for patent above referred to.

In Fig. 1 is illustrated a window, the frame of this window including the vertically disposed members 3 within which

there is mounted an exterior sash-frame comprising hollow side bars 4, illustrated in detail in Fig. 2. The outer faces of these side bars 4 are formed by curved plates 5 which are illustrated as hinged at 6 so as to open when desired to permit the insertion of weights or the replacement, removal or repair of the locking mechanism. The free edge of each curved plate 5 is held to the main body of the sash-frame, in any suitable manner, as by screws 7.

Mounted within the sash-frame are the sliding sashes 8 and 9 whose construction forms no part of my present invention. The sash-frame within which the sliding sashes are mounted is of the casement type and is, therefore, pivotally connected to the frame of the window. To this end the window frame includes the upper and lower transverse members 10 and 11, the upper and lower plates respectively, of which, are formed with sockets 12 for the insertion of pintles 13 and 14. The plate 5 is also perforated at 15 for the passage of laterally projectable bolts which engage with the face of the window casing 2. With the construction of window illustrated in Fig. 1 it is possible to project the pintles 13 and 14 on one side of the window so that the window will be pivoted upon that side and retract the pintles on the other side of the window so that this side of the window may be free to move. If it be desired for any reason that the window shall open in a reverse direction, then the first named set of pintles are withdrawn from engagement with the window casing and the second named set of pintles is projected. It is for the purpose of providing means for withdrawing these pintles and also withdrawing the latching bolts which engage the side members of the window casing that I have provided mechanism illustrated in Figs. 2, 3, 4 and 5, it being one of the objects of my invention to so construct this mechanism that the means for projecting or retracting the pintle bolts 13 and 14 will be independently operable from the mechanism for projecting the latching bolts. The mechanism for this purpose is most clearly shown in Figs. 4 and 5. For the support of the bolt actuating device the plate 5 is formed on opposite sides with the inwardly projecting annular bearings 16 and 17, respectively. Mounted within the annular bearing 16 is an annular sleeve 17, the outer end of which extends out through the front of the casing and is formed with a knob 18 whereby the sleeve may be rotated. The sleeve at its inner end is countersunk as at 19 and disposed within this countersink is a barrel 20 illustrated in detail in Fig. 5. Disposed within the barrel 20 is a shaft 21, the ends of which are formed with longitudinally extending relatively short

kerfs or grooves 22 and 22^a. This shaft has 65 a length equal to the barrel 20. The extremity of the barrel 20 projects slightly into a thimble 23 which is rotatably mounted within the bearing member 17, the inner end of this thimble being outwardly flared as at 70 24. It will thus be seen that the barrel 20 is mounted for rotation around its longitudinal axis and that the shaft 21 is also mounted for rotation around its longitudinal axis. The barrel 20 is longitudinally 75 slotted at diametrically opposite points at both ends as at 25 and 26 and at its middle is formed with an arcuate slot 27 which aligns with a screw threaded perforation 28 formed in the shaft 21.

A screw 29 extends through the sleeve 17^a and engages the adjacent end of the barrel 20 so that the sleeve 17^a and the barrel 20 rotate together. Mounted upon the barrel 20 is a collar 30. This collar is provided 80 with a slot 31 through which a screw 32 passes which enters the slot 27 and engages the perforation 28 in the shaft 21. The collar 30 has a tubular extension 33 projecting tangentially from one side and into which 85 the slot 31 opens and mounted in this tubular extension 33 is a latching bolt 34. The pin 32 which is carried by the shaft 21 projects through the slot 27 of the barrel 20 and the slot 31 of the collar 30 and is connected to the bolt 34 by means of a link 35 and disposed within the extension 33 between the bolt 34 and a stop 36 is a coil 90 spring 37 which normally tends to project the bolt. It will be obvious now that a rotation of the shaft 21 in a counter-clockwise direction in Fig. 3 will cause a retraction of the bolt 34 against the action of the spring 37, the collar 30 remaining stationary.

Mounted upon the collar 30 and extending 105 over the slot 31 is an arcuate spring 38, the extremity of which is formed with a detent tooth 39. This tooth is adapted to engage over the head of the screw 32, as illustrated in Fig. 3, when the shaft 21 is rotated so as 110 to retract the bolt. The spring 38 is of sufficient strength to hold the bolt 34 retracted when the parts are in the position shown in Fig. 3, but yet not prevent the proper manipulation of the bolt to project 115 it. It will be seen that when the bolt is projected the detent 39 will engage behind the head of the screw 38 and thus resist the inward movement of the bolt. The spring 38 is held to the collar 30 by means of a 120 screw 40 extending into the perforation 41 formed in the collar 30. The extremity of the extension 33 is intended to be engaged with the perforations 15 in the plate 5 through which the bolt is projected, as illustrated in Fig. 3, and this extension merely 125 acts as a guide for the bolt.

For the purpose of operating the pintle

bolts 13 and 14 I mount upon the barrel 20 the collar 42 illustrated in detail in Fig. 5, this collar being held in place on the barrel 20 by means of a set screw 43 or in any other suitable manner. The collar 42 is provided at opposite points in its middle with pairs of arms 43 between which the inner ends of the pintle bolts 13 and 14 are pivotally supported, as illustrated clearly in Fig. 2. It will be obvious now that a rotation of the barrel 20 in one direction through the action of the knob 18 will withdraw the pintle bolts from their projected position and that a rotation of the knob 18 in the other direction will act to project the pintle bolts.

Mounted upon the collar 42, as illustrated in Fig. 2 is a spring detent 46, the extremity of which is formed with a slightly depressed portion adapted to engage with shallow recesses 47 and 48 formed in the bearings 17. This spring 46 forms a tooth holding the collar set in either of its rotated positions.

For the purpose of operating the shaft 21 I dispose within the bore of the knob 18 and the sleeve 17 a spindle 49, the extremity of which is provided with a small knurled knob 50. The inner end of this spindle 49 is formed with oppositely disposed teeth 51 projecting longitudinally of the spindle, which teeth are adapted to engage in the grooves 22 formed at one end of the shaft 21. As before stated the barrel 20 is provided at one end with slots 26 and at the opposite end with slots 25. This permits the barrel 20 and the shaft 21 to be operated from the exterior by means of keys A and B, as shown in Fig. 4. Key A is formed with the relatively widely spaced longitudinally extending teeth *a* which are adapted to engage with the notches 25. The key B is provided with the teeth *b* which are so positioned and of such width as to engage the grooves 22^a only when the key is placed in position. By inserting the key A, therefore, the barrel 20 may be rotated to thereby retract or project the pintle bolts, and by inserting the key B the shaft 21 may be rotated to thereby project or retract the latching bolt 34.

As seen in Fig. 2 there is a locking mechanism of the character heretofore described at each side of the window engaging with the adjacent casing wall. In one of these locking devices the pintles are projected so as to form a pivot for the window while the latching bolt 34 is normally retracted. At the opposite side of the window, that is, the side edge which is free, the pintle bolts are normally retracted and the latching bolt 34 only projected when the window is closed to hold the window shut.

As before stated, I primarily design my mechanism for use with the window illustrated in Fig. 1, where it may be desired to

change the pivotal center of the window 65 from one side to the other. In this case it is only necessary to remove a screw 52 which passes through a slot 53 formed in the bearing 16 and which also passes through a slot 54 formed in the sleeve 17^a and which engages with the spindle 49, thus holding the spindle in place and also holding the sleeve 17^a in place and preventing any pulling out of the sleeve or spindle. By removing this bolt 52 the sleeve 17^a may be withdrawn, as 75 may also the spindle 49 and the spindle and sleeve may then be shifted from one of the locking devices to the other, thus practically rendering one of the locking devices inoperative and the other operative. It will of 80 course be obvious that the knob 18 and the spindle 49 are to be disposed on the free or movable side of the window, there being no knob upon the locking mechanism on the other side of the window which will prevent accidental tampering with the pintles or with the latching mechanism. If it be desired, however, to withdraw the pintles upon the pivot side of the window so as to 85 permit the window to be taken out, for instance, or if it be desired to throw the latching bolt on the pivot side of the window, then the shaft 21 and barrel 20 on that side of the window may be operated by means of keys of the type shown in Fig. 4 and lettered 90 A and B. If it be desired to lock the window particularly securely, it is obvious that the latching bolt may be projected on the pivoted side of the window and that on the free side of the window the pintle bolts may 95 also be thrown or projected, thus acting as locking bolts, the free edge of the window then being locked at three places, viz., at the top and bottom and on the edge. It is for 100 the purpose of obtaining access to the interior of the compartments 4 that I hinge the 105 plate 5.

In Figs. 6 and 7 I show my invention as applied to a door and I wish it distinctly understood that while I have shown it used on 110 a house door, the invention may equally well be applied to doors of any construction, such as doors of vaults, safe deposit boxes, or like structures. In these figures C designates the door and D the door-frame. As illustrated, 115 the sill and lintel of the door are provided with sockets 12^a of precisely the same form of the sockets 12, heretofore described. The door is recessed to receive the locking mechanism which is the same as that described, 120 this locking mechanism being provided with the vertically extending pintle bolts 13^a and 14^a. The locking mechanism is controlled by knobs and keys in precisely the same manner as shown in Figs. 2, 3 and 4, and has 125 exactly the same construction.

In order to permit the door to be rotated it can be set in a slightly deep recess and

rotated flat against the wall and I form the sockets 12^a arcuate, as illustrated clearly in Fig. 6 so that when the door swings into the dotted line position shown in Fig. 6, the 5 pintles 13^a and 14^a on that side of the door will travel through the arcuate slot and thus permit the door to be shifted flat against the wall. It will be seen that the arcuate slot 12^a on the free side of the door does not 10 prevent the pintle bolts from acting to lock the door when they are projected.

In Fig. 8 I show a modification of the construction shown in Fig. 4 in which the outer barrel is adapted to project the latching bolt 15 while the inner shaft is adapted to project the pintle bolt, this inner shaft being entirely key actuated so as to prevent any accidental throwing of the pintle bolts. In this form of the device the plate 5 is provided on opposite sides with inwardly projecting bearings 16 and 17, as previously described. Disposed within the bearing 16 is the sleeve 55 which has formed with it the knob 56 whereby the sleeve may be manually rotated. Disposed within the inner end of this sleeve 55 is the barrel 57 to which the sleeve is fastened by means of the set screw 58 so that the barrel rotates with the sleeve. Surrounding the barrel is the collar 59 which 30 has the same form as the collar 30, previously described, and operating through the slot 60 in this collar is the pin 61 which corresponds in every respect to the pin 32, previously stated, except that it is fastened 35 on the barrel and not upon the central shaft. This pin 61 is operatively connected to the bolt 62, as shown in Fig. 11, so that a rotation of the handle 56, the sleeve 55 and the barrel 60 will cause a projection or a retraction 40 of the bolt. Also mounted upon the sleeve 57 is the collar 63 which corresponds to the collar 42 and is operatively connected to the upwardly and downwardly extending pintle rods 13 and 14, in the same manner as 45 is the collar 42. For the purpose of operating this collar 63 and thereby throwing the pintle rods in or out of operative position, the collar is connected to the central shaft 64 by means of the pin 65 which passes 50 through the slot 66 formed in the collar 63. The shaft 64 has exactly the same form as the shaft 21 and is notched at its ends as at 67 for engagement by a key. A thimble 68 is disposed within the bearing 17 and supports 55 the forward end of the sleeve 57. It will be obvious now, that upon a rotation of the shaft 64 the pintle bolts will be retracted or projected and that upon a rotation of the sleeve 57 the latching bolt will be projected 60 or retracted. The latter is accomplished by rotating the knob 56 but rotation of the shaft 64 can only be accomplished by means of a key such as the key B in Fig. 4 having lugs 6 which will engage the notches 67 on

the ends of the shaft. Thus, while the latching bolt may be manually projected or retracted the pintle bolts cannot be actuated except through the use of a key. 65

In Figs. 9 and 10 I show my invention as applied to a safe deposit box or like structure. In these figures 69 designates the wall of a safe deposit vault and 70 designates the box which is slidable into the compartment 71 and out from said compartment. This box has a front wall 72 and an intermediate wall 73 and a rear door 74 which can only be opened when the box is withdrawn. The box is held within the compartment 71 by means of vertically extending bolts 75 and 76 and the laterally projectable latching bolts 77. The operating mechanism for these bolts 75, 76 and 77 is designated generally 78 and is of exactly the same construction as the operating mechanism illustrated in Figs. 2, 3 and 4 except 80 that the mechanism is made to be operated entirely by keys in the manner shown in the right hand side of Fig. 4 and is not operated by knobs. The bolts and the bolt operating mechanism are all contained in the 85 space between the front wall 72 and the intermediate wall 73. In this case it will be noticed that the members 75 and 76 both operate as locking bolts and not as pintle bolts and that two keys are necessary to 90 operate the bolt throwing mechanism, one key operating the laterally projecting bolt and the other operating the vertically projected bolts. It will be obvious that a set 95 of four keys may be used so as to operate these bolts, one pair for each of the locking mechanisms, the keys being different so that thus an additional security is provided. 100

It will be seen from what has gone before that while I have designed my operating 105 mechanism primarily for use with the door or window for the purpose of throwing or retracting pintle bolts and latching bolts, yet it may be largely adapted for a number of other purposes and it is for this reason that I have illustrated the application of my device to a safe deposit box where the box is entirely withdrawable from the bolt. The same locking means, however, may be used upon a hinged door, if desired. 110

While I have illustrated what I believe to be the best form of my invention I do not wish to be limited to the details of construction as it is obvious that many changes might be made without departing from the 115 spirit of invention.

It will be seen that I have provided a lock which is also a hinge so constructed that by the use of two of these hinge locks the pivotal point of the door may be shifted from 120 one side to the other, if desired. Further, it will be seen, that when in use, and when both of the locking or bolt-operating mecha-

nisms are used the door is held at six points. Further, that I provide a door locking and hinging construction requiring the use of two keys and operating members in order to 5 secure a complete operation of the mechanism. This gives extra security to all buildings and at the same time permits of the window or door being swung from either side. The lock or hinge is concealed within 10 the door itself, nothing but the keyhole or the knob whereby the device is operated being visible from the outside.

One of the principal features of my invention lies in the fact that the door or 15 window can be unhinged in a moment so that the whole door may be removed without the necessity of taking off the hinges. This permits the ready removal of the door 20 to allow furniture, pianos, or like bulky objects to be moved through the doorway.

A further advantage of the construction lies in the fact that when all of the bolts are shut the door is shut tight at every point. This keeps the doors from warping inwardly at the upper and lower corners above 25 the usual lock. Again it must be reiterated that while I have illustrated my invention as applied to a door or window or safe de- 30 posit box, that it is not limited to this application, as it may be used for safety doors, for boxes, trunks, lockers, or in many other situations.

Having thus described the invention what is claimed as new is:—

35 1. In combination, opposed hollow bearings, independent bolt-actuating members having a concentric arrangement and supported between said hollow bearings, elements mounted concentrically in one of the 40 said hollow bearings and connected with the respective bolt-actuating members, and means insertible in the other hollow bearing to admit of operating one or the other of the bolt-actuating members.

45 2. Bolt operating means including concentric bolt-actuating members, a pin and slot connection between such members to prevent relative longitudinal movement but admit of a limited independent rotary movement, and concentric elements held against longitudinal movement but having a limited independent rotary movement and connected to the respective bolt-actuating members to admit of independent operation thereof.

55 3. In combination, opposed bearings, concentric bolt-actuating members supported by said bearings, concentric elements mounted in one of the bearings and connected with the respective bolt-actuating members, and 60 means for retarding the movement of one of the bolt-actuating members connected thereto and frictionally engaging the other one of said bearings.

4. The combination with a casing having

an opening, the upper wall of which is 65 formed with spaced sockets and the lower wall of which is formed with spaced sockets, the side walls being formed with laterally projecting sockets, of vertically movable bolts, one for each socket, transversely mov- 70 able bolts, one for each socket, and oppositely disposed bolt-operating devices, each including concentric rotatable members, one of the members of each pair being connected to the laterally projectable bolt on that side 75 while the other member of the same pair is connected to the vertically movable bolts on that side.

5. The combination with a door or window casing, having pintle bolt recesses on 80 each side thereof at its upper and lower ends, and laterally projecting latching bolt recesses disposed in the side walls of the casing, of a door therefor, a pair of vertically movable pintle bolts disposed adjacent each side edge of the door and movable to a projected or a retracted position, rotatable means for projecting or retracting the pintle bolts, laterally projectable latching bolts mounted on the door adjacent each 90 side edge, and rotatable means for projecting the latching bolts independently of the pintle bolts, the two rotatable means having a concentric arrangement and adapted to be independently operated from one side of 95 the door.

6. In a bolt throwing mechanism, a central shaft, an outer barrel, said barrel being circumferentially slotted, a pin projecting from the central shaft through said slot, 100 bolt-operating mechanism connected to said pin, a collar fixedly mounted upon the barrel to rotate therewith, bolt operating mechanism connected to said collar, and independent means for operating either the 105 shaft or the barrel.

7. In a bolt operating mechanism of the character described, a central shaft, a barrel surrounding the shaft and circumferentially slotted, a pin projecting from the 110 shaft and through said slot, a bolt to which the pin is operatively connected, a collar rigidly mounted on the barrel to rotate therewith, a bolt to which the collar is operatively connected, the shaft being formed at one end with a key-receiving slot and the barrel being formed at one end with a key-receiving slot.

8. In a bolt operating mechanism of the character described, a central shaft, a barrel surrounding the shaft and circumferentially slotted, a pin projecting from the 120 shaft and through said slot, a bolt to which the pin is operatively connected, a collar rigidly mounted on the barrel to rotate therewith, a bolt to which the collar is operatively connected, a central shaft engaging the first-named shaft and formed with a 125

knob, a sleeve surrounding the last-named shaft and formed with a knob adjacent the first-named knob, the inner end of the sleeve engaging with said barrel, and means for locking the second named shaft and the surrounding sleeve to the first-named shaft and said barrel.

In testimony whereof I affix my signature in presence of two witnesses.
